DOOR HINGE

James Vani, Chicago, Ill., assignor to Chicago Metal Mfg. Co., Chicago, Ill., a corporation of Illinois

Application July 26, 1940, Serial No. 347,725

4 Claims. (Cl. 16—131)

My invention relates to doors.

It is particularly applicable to and will be illustrated and explained in connection with doors for so-called "smoke ovens" wherein meats, such as hams and bacon, are smoked or "cured," although doors embodying the invention have a wider application. In smoking meats, for example, it is highly desirable that the smoke be applied under considerable pressure to insure more speedy and proper penetration. For obvious reasons the escape of smoke from the chamber in which the treatment takes place is undesirable, but smoke-tight doors which, at the same time, may be readily opened and closed have not heretofore been available. Trouble has been particularly in evidence at the hinge edges of the doors and between the panels of double doors.

The principal object of my invention is to provide a gas-tight door—one from which smoke, for example, and other gases under considerable pressure cannot escape.

Another object is to improve the seal at the hinge side of a swinging type door.

Another object is to provide an improved seal between panels of a double door.

Another object is to provide a door which, when open, can be swung completely back and out of the way.

A further object is to provide a tight door that is reliable, easy to operate and of simple construction.

Other objects and advantages will hereinafter appear.

Two embodiments of my invention—one in a single door and one in a double door—are illustrated in the accompanying drawings wherein:

Fig. 1 is a front elevation of a single door—closed and in fully sealed and latched condition;

Fig. 2 is an enlarged section on the line 2—2 of Fig. 1;

Fig. 3 is a section similar to Fig. 2, with the door closed, but unlatched, and with the seal uncompleted;

Fig. 4 is a front elevation of a double door—closed and in fully sealed and latched condition;

Fig. 5 is an enlarged section on the line 5—5 of Fig. 4;

Fig. 6 is a section similar to Fig. 5, with the door closed, but unlatched, and with the seal uncompleted;

Fig. 7 is a section on the line 7—7 of Fig. 4;

Fig. 8 is a section on the line 8—8 of Fig. 4;

Fig. 9 is an enlarged broken section on the line 9—9 of Fig. 4;

Fig. 10 is an enlarged section on the line 10—10 of Fig. 4;

Fig. 11 is a section similar to Fig. 10, with the door latching mechanism in an intermediate position;

Fig. 12 is an enlarged section on the line 12—12 of Fig. 4;

Fig. 13 is an enlarged section on the line 13—13 of Fig. 9;

Fig. 14 is a section on the line 14—14 of either Fig. 1 or Fig. 4;

Fig. 15 is a section on the line 15—15 of Fig. 4 or Fig. 1 (reversed); and

Fig. 16 is a section on the line 16—16 of Fig. 15.

In general, the illustrated embodiments of my invention include a frame about a doorway and one or more panels for closing the doorway, outer margins of a panel and inner margins of the doorway frame—and, in the case of double doors, adjacent margins of the two closure panels—having complementary confronting sealing elements—at least one of which is elastic—which, when pressed sufficiently tightly together, provide an effective gas-tight seal therebetween.

Each panel or door proper is supported upon one or more hinges which are of a type permitting the panel to be swung about a pivot to open and closed positions and, in addition, when the panel is in closed position and properly latched at its outer or unhinged edge, enabling the panel, in the hinged region, to be moved inwardly substantially transversely of the plane of the doorway to bring the sealing elements, particularly along and in the regions adjacent the hinge edge of the panel, into tighter engagement. Manually actuated mechanism is provided for tightly shutting and latching the outer or unhinged edge of a panel in closed and sealing position and also for then moving the hinged edge inwardly to bring tightly together the sealing elements in the hinged region and latching it to maintain this condition until released.

A single door construction will be first described, initial reference being particularly to Figs. 1, 2 and 3.

Fig. 1 shows the front of a smoke oven in the form of a cabinet 5 of any appropriate construction. Its doorway 6 is closed by a door proper or closure panel 7. The doorway is bounded on all sides by a doorway frame 8, the principal function of which is to provide a suitable mounting for one of the confronting complementary sealing elements hereinafter described. The closure panel 7 is hinged along one vertical edge

(three hinges 9 being shown) so as to be capable of swinging horizontally to open and closed positions. Preferably, for smoke ovens at least, the doorway frames and panels are made of metal.

Along its four sides the doorway frame 8 has an inwardly projecting continuous flange 15 which forms an abutment for a secondary sealing strip 16 of suitable elastic material, such as rather soft rubber, carried by the closure panel 7 near its edges. Preferably this sealing strip 16 is formed with a body 17 which is normally somewhat cylindrical, as shown in Fig. 3, but which upon the final sealing movement of the panel to be later explained, is brought tightly against the flange 15 and compressed and flattened as shown in Fig. 2. The anchorage of secondary sealing strip 16 to the edge of the closure panel may be effected in various ways, such as providing it with a fin 18 adapted to be clamped and secured between the back side of the panel and a projecting flange of one of the elements of a primary seal to be now described.

The primary seal includes an elastic element 20 preferably of rather soft rubber, which lies along the inner margin of the doorway frame, and a rib 21 extending along the margin of panel 7 a short distance inside of elastic element 16 of the secondary seal. Preferably, as shown in Figs. 2 and 3, the inwardly projecting rib 21 may be formed by folds in the metal sheet constituting the inner face of the closure panel, the extreme edges of the sheet being utilized to clamp upon and anchor the fin 18 of the elastic element 16 of the secondary seal. The elastic element 20 of the primary seal is held in place within the channel 22 of a seal support 23 forming a part of the doorway frame. When the panel is forced into sealing position, as will be hereinafter explained, the metal rib 21 on the closure panel compresses and is transiently embedded in the elastic element 20, as shown in Fig. 2.

Thus, the doorway and the outer margin of the closure panel are bounded by complementary confronting sealing elements carried by the doorway frame and the panel respectively, and which, upon being tightly pressed together as shown in Fig. 2, results in a compressing of the elastic elements—in fact, as to the primary seal the actual embedding of one element into the other—to provide an effective seal through which gas, even under considerable pressure, cannot escape.

In order that the closure panel may be freely and easily swung between open and closed positions without appreciable pressure upon the sealing elements along the hinge or inner edge thereof during movement, and yet to provide the necessary movement to enable the sealing elements to be forced tightly together after the door is closed, the hinges 9 are of a type which permits of dual movements of the panel. These movements are, in closing, first a swinging or pivotal movement about the hinge pivot axis to bring the panel from open to closed positions and then a slight pivotal movement about the unhinged or outer edge—a movement so slight that it is practically a rectilinear movement inwardly of the hinge edge. In opening the door the movements are, first, an outward movement of the panel at its hinge or inner edge, which is substantially perpendicular to the plane of the doorway, and then a pivotal movement about the hinge axis to swing the panel clear of the doorway.

Since the hinges 9 may all be alike, only one needs be described. A hinge includes a resilient

or spring metal strip 30 pivotally connected to the doorway frame at one end and pivotally connected to the closure panel, preferably in the transverse mid region, at the other end. Of course, it is not necessary that the pivot about which the closure panel swings be carried by the doorway frame in any strict sense of that expression; it may, for example, be carried by the wall of which the doorway frame forms, in effect, only a part. For this reason the expression "doorway frame" is not to be taken in its strict technical sense, but, rather, to include any appropriate part of the structure to which the movable closure panel may be pivotally attached.

How the pivotal connections are effected is immaterial. As shown particularly in Figs. 2 and 3, one end of the strip 30 may be bent around to form a bearing 31 for a pintle 32. Pintle 32 is supported at opposite ends in ears 33 of an attaching bracket 34 which may be secured to the doorway frame in any suitable manner, such as by screws 35. In a similar manner the other end of strip 30 may be bent around to form a bearing 36 for a pintle 37 supported at opposite ends in the ears 38 of an attaching bracket 39 which may be secured to the front face of the closure panel by suitable means such as screws 40.

The resiliency of the closure panel supporting hinges is utilized to effect the final sealing movement of the hinged or inner edge of the panel through the cooperation of pressure controlling mechanism located intermediate the hinges and panel and manually operable either to flex or tension and to release the tension in the spring hinges. Upon the flexing or tensioning of the spring hinges, the inner edge of the panel is given the final inward movement which forces the sealing members tightly together to effect the final seal; upon the release of tension in the spring hinges, the inner edge of the panel is moved slightly outward to relieve the sealing compression, as previously explained. Inasmuch as the manually actuated pressure controlling mechanism for all of the hinges may be alike, only one mechanism will now be explained in detail.

Intermediate its ends the hinge strip 30 is loosely secured to the panel by means of a U-shaped yoke 45 which lies loosely between the upstanding flanges 46 of a bracket 47. Yoke 45 straddles and is rigidly attached to spring strip 30 by screws 48 and bracket 47 is rigidly attached to the front face of closure panel 7 by screws 49. A cam disc 50 is located within the yoke 45 to bear against both the yoke and strip 30. Disc 50 is eccentrically mounted upon an operating shaft 55 which is journaled in the upstanding flanges 46 of bracket 47. Adjustability of the relation between the shaft, eccentric disc and of the engagement of the disc with yoke 45 and strip 30 is attained by securing the disc to the shaft by a set screw 56.

As shown in Fig. 1, shaft 55 is of a length to underlie all of the hinges 9 with which a closure panel may be equipped and at each hinge it is equipped with an eccentric disc 50 located within the socket formed by yoke 45 and hinge strip 30. Thus, upon rotation of shaft 55 in one direction, the eccentric discs 50 may all be rotated to cause hinge spring strips 30 to exert pressure upon the panel in the region of its hinge edge to force it inwardly transversely of the plane of the doorway, so as to bring more closely together the panel and doorway frame in that region and firmly press together the sealing elements carried

thereby, as shown in Fig. 2. Rotation of shaft 55 in the opposite direction will release the tension in spring hinges 38 to move the hinge edge of the panel outwardly to increase the separation between the panel and doorway frame and release the pressure between the sealing elements carried by them, as shown in Fig. 3.

Shaft 55 is adapted to be rotated by a suitable handle such as 60, shown in Figs. 1, 15 and 16. Handle 60 is hinged upon a pivot 61 to and between the ears 62 of a collar 63, which collar is in turn rigidly attached to shaft 55 in any appropriate manner. In its normal or doorway closed position handle 60 lies in the open-topped socket of a holding member 64 which is, by screws or otherwise, secured to the front face of the closure panel (see Figs. 1, 15 and 16). In this normal position of handle 60, as shown in Fig. 1, the shaft 55 is turned so that its cam discs 59 have forced the hinge edge of the panel rearwardly or inwardly with the sealing elements in compressed sealing relation as shown in Fig. 2; and this relation is retained as long as handle 60 is held by the socket in the holding member 64. When it is desired to release the hinge edge of the door, handle 60 is rocked upwardly about pivot 61 until it passes out of the socket of holding member 64, whereupon the handle is free to be swung horizontally to turn shaft 55 to rotate cam discs 59 to move the hinge edge of the door forwardly or outwardly to release the compression between the sealing elements, as shown in Fig. 3.

The outer or unhinged edge of the door is forced into closed sealing position and there held by a manually actuated latch mechanism operated by a handle 70 and the details of which are shown in Figs. 2 and 3. Handle 70 is pivotally carried by an operating shaft 71 through a knuckle joint 72 and is latched in normal or doorway-closed position by a socketed holding member 73 essentially identical to those heretofore described for handle 60. Shaft 71 is journaled in a bracket 75 suitably secured, by screws or otherwise, to the front face of closure panel 7 and carries for each of the several latches at the outer edge of the panel (three being shown in Fig. 1) a bifurcated crank 76 adjustably secured thereto by a set screw 77.

Each crank 76 has a bolt member 78 pivotally attached thereto between its bifurcated ends on a pin 79. Bolt 78 is provided with a slot 80 in which lies a pin 81 anchored in and extending between the outwardly projecting flanges 82 of bracket 75. The forward end of each bolt 78 is adapted to be received by a socket member 83 which is attached in alignment with the corresponding bolt to the front face of the door panel by screws or other appropriate means. By horizontal rotational movement of handle 70 the shaft 71 may be rotated to cause cranks 76 to withdraw the bolts 78 from sockets 83, as indicated in Fig. 3. Reverse rotational movement of handle 70 causes cranks 76 first to project the bolts 78 into the corresponding sockets 83 and then, upon further movement after the ends of bolts 78 lie in the sockets 83, to cause the thrust of the ends of the bolts against the front walls 84 of the sockets 83 to force the outer or unhinged edge of the closure panel rearwardly from a condition indicated by Fig. 3 to the condition indicated by Fig. 2, wherein the complementary sealing elements on and in the regions adjacent the panel and doorway frame are compressed tightly together to effect a tight seal between them.

Briefly summarized, the operation of the single

door is this: Assuming the closure panel 7 to be in unlatched condition as indicated in Fig. 3, it may then be freely swung clockwise about the vertical axis of hinge pivots 32 until the doorway is completely open. In fact, the closure panel may be swung around almost against the side wall of the oven. During such swinging movement—and also in swinging the panel to closed position—there needs be at no time any appreciable contact and pressure between the sealing elements along the hinge edge of the panel. Thus, the swinging of the door is unimpeded by the sealing elements. Now to close and seal the door the panel is swung horizontally about the vertical axis of hinge pivots 32 from open position until it blocks the doorway as shown in Fig. 3. Then latch handle 70, which previously has been standing outwardly to withdraw bolts 78, is turned so as to project bolts 78 into sockets 83 and then still further rotated to cause the ends of bolts 78 to thrust against the front walls 84 of sockets 83, as previously described, and force the outer edge of the closure panel inwardly, so as tightly to compress together the sealing elements along the outer edge and also throughout a portion of the top and bottom edges. To retain the outer edge of the closure panel in this sealing condition, handle 70 is swung downwardly about the pivot of knuckle 72 to a position within the socket of holding member 73. Finally, handle 60, which up to now should be standing outwardly to hold the hinge edge sealing elements in the uncompressed condition shown in Fig. 3, is turned to rotate the shaft 55 and permit the bias of the spring hinge strips 38 to force the hinge edge of the closure panel toward the doorway frame and thereby tightly compress together the sealing elements along the doorway edge and also throughout the top and bottom edges in the regions near the hinge edge. Now by swinging the handle 60 downwardly about pivot 61 until it is in position to be retained in the socket of holding member 64 the door is latched closed with the closure panel throughout its margin tightly sealed against the panel.

In opening the door from sealed condition, the hinge edge is first released by lifting handle 60 out of its socket in the holding member 64 and rotating it so as to turn the eccentric discs 59 50 and thereby relieve the thrust of hinge strips 38 and enable the hinge edge of the closure panel to move outwardly away from the plane of the doorway frame and release the compression between the complementary sealing elements along 55 the hinge edge. Next, the outer or unhinged edge is released by lifting handle 70 from its socket in holding member 73 and then rotating it to effect the release and withdrawal of all of the bolts 78. The closure panel is now ready to be 60 swung about the axis of hinge pivots 32 completely to open the door.

The double door construction will now be described, initial reference being particularly to Figs. 4, 5 and 6.

Fig. 4 shows the front of an oven 105 having a doorway 106 closed by two closure panels 107 and 107'. The doorway is bounded by a doorway frame 108 on which are pivotally mounted the desired number of panel supporting hinges 109—three being shown for each door panel. The doorway frame and the top, bottom and hinge edges of each closure panel carry complementary secondary sealing elements 115 and 116 and complementary primary sealing elements 120 and 121 such as previously described. The adjacent

or unhinged edges of the two closure panels are equipped with somewhat different sealing elements, as will later appear.

Each hinge is equipped with a pressure cam disc 150—all of the discs for the hinges supporting panel 107 being adjustably mounted on an actuating rod 155 and all of the discs for the hinges supporting panel 107' being adjustably mounted on an actuating rod 155'. Actuating rods 155 and 155' are operable by handles 160 and 160', respectively, which handles are, in door sealing position, adapted to be retained in the sockets of holding members 164 and 164', respectively.

Thus, in so far as the hinge edges are concerned, each panel of the double door is pivotally carried by resilient hinges permitting dual movements of those edges, is equipped with elastic sealing elements confronting complementary elements on the doorway frame when the door is closed, and has manually actuated seal compressing and latch mechanism essentially identical in structure, method of operation and result to a single door, such as heretofore explained in detail.

The two panels are sealed together along their inner or unhinged edges in a somewhat different manner. This will now be described, with special reference to Figs. 5 and 6.

Panel 107 is provided along the edge confronting panel 107' with a metallic seal strip 200. This strip is secured to and attached to the panel 107 by a plate 201 and screws 202. It lies in a recess 203 behind a ledge 204 of panel 107 overhanging the extreme edge of the panel in position to contact with a compressible sealing element along the outer edge of the panel 107', as will be apparent from Figs 5 and 6 and as will presently be described.

Between seal strip 200 and panel ledge 204 there is provided suitable seal filling 205 so that no leakage of gas may occur between the seal strip 200 and the panel to which it is attached. Panel 107' is provided with a complementary recess 210 and ledge 211 along its unhinged edge with a compressible sealing element 212 carried and supported on the ledge. Preferably this sealing element 212 is of soft rubber and it may be formed and secured in place on ledge 211 in any suitable manner, such, for example, as in essentially the same way as the strips 116 are secured along the hinge edges.

The two closure panels 107 and 107' are provided with cooperating compressing mechanism whereby their outer or unhinged edges may, after the panels are swung to door-closing positions as indicated in Fig. 6, be drawn firmly toward each other to clamp the compressible sealing element strip 212 of panel 107' tightly against the metallic sealing strip 200 of panel 107, preferably to the extent that the compressible strip is flattened and compressed as shown in Fig. 5, thereby sealing the joint between the two panels. This compressing mechanism includes one or more levers 215 (these being shown in the drawings) which are carried by panel 107 and adapted to be projected forwardly and bear against pressure plates 216 carried by panel 107'.

Each lever 215 is pivotally connected to the bifurcated end of a bell crank 217 by a pin 218 and is provided with a slot 219 accommodating a fixed pin 220. The levers 215 are adjustably attached to an operating shaft or rod 225, by a set screw 226. Shaft 225 is journaled in the upstanding spaced flanges 227 of brackets 228,

there being a bracket for each lever 215. Flanges 227 of each bracket flank the associated bell crank 217 and lever 215 and between them lies the pin 220 which at opposite ends is anchored thereto. Actuating rod 225 is provided with an actuating handle 229 fixed thereto by a knuckle 230—this knuckle causing the handle to rotate the shaft when the handle is swung in a substantially horizontal plane, but permitting the handle to be rocked vertically above pivot 231 and thus enable it to be lowered into the socket of a holding member 232 and thereby prevented from horizontal movement or to be raised from the socket and thereby freed for horizontal movement to rotate shaft 225. Thus, with the panels swung shut, but unsealed along the unhinged edges and the compressing mechanism retracted as indicated in Fig. 6, the handle 229 may be moved horizontally to rotate shaft 225 and thereby project forwardly all of the levers 215. The levers 215 first move forwardly across the space between the two confronting outer panel edges and then, because of the compound movement imparted to them by the pivotal connections with the levers 217 and the sliding connections between slots 219 and fixed pins 220, their forward ends engage the pressure plates 216. Further effort on handle 229 causes the confronting outer panel edges to be forced into alignment, resulting in the compressible sealing strip 212 being tightly clamped against the metallic sealing strip 200 to effect the seal between the outer panel edges as indicated in Fig. 5.

The operation of handle 229 to effect the outer edge seal (i. e., the seal between the confronting edges of the closure panels) as just explained also serves to operate latching mechanism for holding the panel of the door in closed sealed condition. To accomplish this result shaft 225, which, as before stated is turned by handle 229, has a sleeve 240 feathered thereto near one end, each sleeve being rotatable with shaft 225 and yet capable of limited longitudinal movement therealong. Each sleeve is provided with a cam-shaped latch bolt 241 which is adapted, under conditions to be presently explained, to cooperate with an abutment 242. Each abutment 242 is attached to the doorway frame by a stirrup-like bracket 243—which is anchored to the frame by screws 244—and is made adjustable toward and from the axis of shaft 225 by an adjusting set screw 245.

Each sleeve 240 is equipped with a projecting stud 250 on the end of which a cam roller 251 is rotatably secured by a screw 252. Each roller 251 lies in a cam formed by the two angled and parallel flanges 253 of a cam bracket 254. Bracket 254 is secured to the front face of panel 107 by appropriate means, such as screws 255.

Thus, upon rotation of shaft 225 by handle 229 in a direction to project the levers 215 to sealing position, sleeves 240—and consequently latch bolts 241 and studs 250 carrying cam rollers 251—are rotated about the axis of shaft 225. At the same time the cam rollers 251 move along the cam grooves provided by flanges 253 and, when the sloping portions of those cams are reached, the sleeves 240 are caused to travel outwardly along shaft 225 to move the latch bolts 241 into alignment with abutments 242 and also to turn the latch bolts into wedging engagement with those abutments. In other words, the latch bolts move from the position indicated by the dotted lines of Fig. 13 into the position indi-

cated by the full lines. Preferably the angular or time relation between the dwell (i. e., horizontal) and active (i. e., sloping) portions of the cams formed by flanges 253 and the compressor levers 215 is such that the latch bolts 241 reach latching position with respect to abutments 242 shortly before the compressing levers 215 reach the limit of their seal tightening condition.

Briefly reviewed, the operation of the double door seal and latch is as follows: Assuming that the doors are closed and latched as indicated in Fig. 4, the handles 160 and 229 are substantially flat against the panel 107, and handle 160' is substantially flat against panel 107', each being there retained against accidental displacement by its respective holding member 164, 164' and 232. In this condition operating shafts 155 and 155' are turned so that the cam discs carried thereby have brought about and retain the seal compressing relation along the hinge edges of the panels indicated by Fig. 5. Likewise, shaft 225 is turned and held so that the compressing levers 215 are projected across to the adjacent edge of the other panel and, by outward pulls exerted on the panel 107 and inward thrusts exerted upon panel 107', have compressed tightly together the sealing strips along the inner or unhinged panel edges as indicated in Fig. 5. Furthermore, shaft 225 is turned so that latch bolts 241 are projected outwardly into alignment with latch abutments 242 and turned so as to engage the abutments and latch the panels in closed and tightly sealed condition as indicated in greater detail by the full lines of Fig. 9.

Now if it is desired to open the door, handles 160 and 160' are first elevated out of the sockets of holding members 164 and 164', respectively, and turned to project outwardly from the plane of the panels. These movements of handles 160 and 160' cause the hinge edges of the two panels to recede from the adjacent doorway frame and release the seal and tight compression between the complementary sealing elements therealong so that they assume the relative positions indicated in Fig. 6. Next, latch handle 229 is raised from the socket of its holding member 232 and turned to project outwardly from the plane of the door panels. This movement of handle 229 withdraws compressing levers 215 to release the seal between the confronting outer or unhinged panel edges, as indicated in Fig. 6, and also withdraws bolts 241 from engagement with abutments 242 as indicated by the dotted lines of Fig. 9. The panels are now unsealed and unlatched and ready to be swung about the axes of hinges 109 to fully door-open position. And during such swinging movements there is no appreciable pressure upon the sealing elements along the hinge edges of the panels.

In closing, sealing and latching the double door, the panels are first swung shut about the axes of their hinges 109. Then the latching handle 229 is swung horizontally from a position where it projects outwardly from panel 107 to the position where it lies along the panel and rocked downwardly to lie in the socket of holding member 232. This movement of handle 229 projects forwardly the compressing levers 215 and causes the adjacent outer panel edges to be drawn into alignment, thereby compressing together the complementary sealing elements therealong into tight sealing relation as indicated in Fig. 5; also it projects the latch bolts 241 into alignment with the associated abutments 242 and turns those bolts to provide the tight

wedging latch action heretofore mentioned. Finally, the sealing handles 160 and 160' are turned from positions in which they project outwardly from panels 107 and 107' to positions in which they lie along those panels, respectively, and rocked downwardly to lie in the sockets of their respective holding members 164 and 164'. These movements of handles 160 and 160' cause the hinge edges of panels 107 and 107' to be forced toward the plane of the doorway frame, with the result that the sealing elements along those edges are tightly forced together into sealing position, as indicated in Fig. 5.

Having thus illustrated and described typical embodiments of my invention, what I claim and desire to secure by United States Letters Patent is as follows:

1. A hinge for a door closure panel comprising, a resilient strip adapted for pivotal connection both to the panel and to the doorway frame, the flexure of the resilient strip permitting the hinge side of the panel to be moved in and out relative to the doorway frame after the panel has been swung shut; and control mechanism located intermediate the two pivotal connections of the hinge strip to effect in and out movements of the hinge side of the panel while the panel is in closed position, said mechanism comprising a U-shaped yoke attached to the hinge strip, a rotatable shaft adapted to be carried in a fixed position relative to the panel, and an eccentric cam disc carried by the shaft and located between and in contact with the yoke and the hinge strip.
2. A hinge for a door closure panel comprising, a resilient strip adapted for pivotal connection to both the panel and doorway frame, the flexure of the resilient strip enabling the hinge side of the panel to be moved in and out relative to the doorway frame after the panel has been swung shut; and mechanism for flexing the hinge strip after the closure panel has been swung shut so as to move the hinge side of the panel in and out relative to the doorway frame, said mechanism comprising a generally U-shaped yoke secured to the hinge strip intermediate its ends, a rotatable eccentric cam lying within the yoke and engaging both the yoke and the hinge strip, and a pivot for mounting the cam with its axis in a fixed position relative to the closure panel so that rotational movement of the cam after the door is swung shut effects flexing of the hinge strip and movement of the closure panel in and out relative to the doorway frame.
3. A hinge for a door closure panel comprising, a resilient strip adapted for pivotal connection to both the panel and the doorway frame, the flexure of the resilient strip enabling the hinge side of the panel to be moved in and out relative to the doorway frame after the panel has been swung shut; and mechanism for flexing the hinge strip and thereby altering the spacing between the closure panel and the strip to effect in and out movements of the hinge side of the panel while the panel is in closed position, said mechanism comprising a yoke secured to and having a bearing surface spaced from the hinge strip and lying between the hinge strip and the closure panel, a rotatable shaft adapted to be carried in a fixed position by and relative to the panel and lying between the hinge strip and the bearing surface of the yoke, and an eccentric cam disc carried by the shaft and located between and in contact with the bearing surface of the yoke and the hinge strip.

4. A door hinge for effecting a tight seal between elastic elements on the closure panel and the doorway frame and comprising, a resilient metallic hinge strip the flexure of which permits the hinge side of the panel to be moved in and out relative to the doorway frame after the panel has been swung shut, a pivotal connection for attaching the strip to the closure panel, a pivotal connection for attaching the strip to the doorway frame, said strip and pivotal connections providing a swinging support for the closure panel on the doorway frame, a yoke located between the hinge strip and the closure panel and

5 attached to the strip, a cam disc located between and in contact with both the hinge strip and the yoke, a rotatable shaft upon which the cam disc is eccentrically mounted, a bracket for attachment to the closure panel and supporting the shaft, and a handle for rotating the shaft so as to rotate the eccentric cam disc and thereby flex the resilient strip and move the hinge side of the panel in and out relative to the doorway frame to compress and release compression between the elastic elements on the closure panel and the doorway frame.
